(57) **CLAIM**

The ornamental design for a control panel for elevator, as shown and described.

DESCRIPTION

FIG. 1 is a front, top and right side perspective view of a control panel for elevator, showing an embodiment of our new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is an enlarged cross-sectional view thereof; taken along line 7-7 of FIG. 2, with the internal system omitted;

FIG. 8 is a reference view showing the panel in use thereof;

FIG. 9 is a reference perspective view with the door opened for maintenance;

FIG. 10 is an alternate front elevation view of embodiment one thereof;

FIG. 11 is another alternate front elevation view of embodiment one thereof;

FIG. 12 is yet another alternate front elevation view of embodiment one thereof; and,

FIG. 13 is yet another alternate front elevation view of embodiment one thereof.

The broken lines shown in FIG. 8 are for the purpose of illustrating environmental structure and form no part of the claimed design.

1 Claim, 10 Drawing Sheets
